FUR PELT OR SKIN STRETCHING
MECHANISM

Carl H. Donner, Summit, and William C. Weber,
Nutley, N. J., assignors to The Chapal Donner
Corporation, Newark, N. J., a corporation of
New Jersey

Application November 11, 1942, Serial No. 465,228

12 Claims. (Cl. 69—27)

This invention relates to mechanism for use in the preparation of fur employed in the manufacture of felt hats or in the production of other felt products; and the invention has reference, more particularly, to mechanism for stretching and smoothing fur pelts or skins preparatory to cutting away the fur or hair therefrom or preparatory to any other desired use of the stretched and smoothed pelts or skins.

The fur of rabbits, hares, nutria, muskrat, beaver and similar animals is largely used as a fur for felting, and especially for the felting of hat bodies. Quantities of the fur pelts or skins of these animals are ordinarily packed in more or less compressed bales or bundles for shipment from the source of supply thereof to fur processors. The fur processors prepare the fur by carotting, dyeing and like treatments, and thereupon cut the fur from the skin, thereby making the same ready for use by the manufacturer of felt hats or other felt products.

Fur pelts or skins, when baled for shipment to the processor, become more or less wrinkled and otherwise distorted in the packing, and tend to dry out and set or more or less stiffen in such condition. Due to such wrinkling or like distortion, when a pelt or skin is subjected to a cutting machine for removal of the fur from the skin, the cutting knives either fail to reach the bases of the hairs so as to cut them off close to the skin, or the knives cut off shreds of skin with the fur without severing the hair therefrom, either of which occurrence results in considerable loss and waste of valuable fur. Such occurrences would be substantially avoided, or at least considerably limited, were the wrinkles or like distortions of the skin smoothed out and removed, so as to leave the skin stretched into substantially flat and smooth condition; in which condition the cutting machine knives can best reach into and sever the hairs at points very close to the skin surface, and with minimum risk of chipping the skin.

Having these things in view, it is an object of this invention to provide a novel mechanism for stretching and smoothing fur pelts or skins.

The invention has for a further object to provide a fur pelt or skin stretching and smoothing mechanism which is quick acting and efficient; and which operates to stretch and smooth the skin progressively from a medial portion outwardly thereof in opposite directions, so that the stretching and smoothing action is equalized and uniformly applied without risk of tearing or other injury to the skin or fur.

Other objects of this invention, not at this time more particularly enumerated, will be understood from the following detailed description of the same.

An illustrative embodiment of a fur pelt or skin stretching mechanism according to this invention is shown in the accompanying drawings, in which:

Fig. 1 is an end elevational view thereof; Fig. 2 is a side elevational view thereof; Fig. 3 is a fragmentary cross-sectional view thereof; and Fig. 4 is a fragmentary horizontal sectional view, taken on line 4—4 in Fig. 2.

Similar characters of reference are employed in the above described views, to indicate corresponding parts.

Referring to said drawings, the reference character 10 indicates a suitable framework for supporting the operative parts of the mechanism; said framework preferably including a lower horizontal platform 11 and an upper horizontal platform 12.

Mounted on the framework above the upper platform 12 is a vertically reciprocable presser member or table 13, which is shaped to provide oppositely extending, downwardly and laterally inclined work supporting faces 14 angularly divergent from a longitudinal medial portion 15 thereof. Said presser member or table 13 is affixed, preferably at a point midway between its ends, upon the upper end of a perpendicular elevator shaft 16. Said elevator shaft is slidably supported in suitable guide bearings 17 respectively affixed to the framework platforms 11 and 12. The presser member or table 13 is supported against rotative displacement or movement about the axis of its elevator shaft 16 by outlying guide rods 18, which are dependent therefrom, and which are slidably movable through guideway members 19 affixed to the upper platform 12.

The framework 10 includes side bracket frames 20 having forwardly projecting bracket arms 21 which are spaced above the presser member or table 13, so as to extend across the line of vertical reciprocatory movement of the latter. Affixed to and extending between said side bracket arms 21 are vertically spaced frame plates 22 and 23.

Disposed above the presser member or table 13, so as to be aligned with and opposed to the longitudinal medial portion 15 of the latter, is a vertically yieldable clamp bar 24. Said clamp bar is carried by spaced vertically movable slide bars 25, which pass through and are guided by

said frame plates 22 and 23. Said clamp bar is yieldably biased for movement toward the presser member or table 13 in any suitable manner. One illustrative means for so biasing said clamp bar comprises weight members 26 which are preferably affixed to the upper free end portions of the slide bars 25; the gravitation of said weights operating to urge the clamp bar toward the presser member or table. Means are also provided for stopping descent of the clamp bar so as to initially space the same above and away from the medial longitudinal portion 15 of the presser member or table, when the latter occupies its normal initial lowered position; and an illustrative form of means for such purpose, as shown, comprises a stopper member 27 which is affixed to the slide bar 25 to a position intermediate plate 23.

Said cam drum 35 is provided around its peripheral surface with a suitably shaped cam member 42 which engages said roller stud 41. Power transmission means is provided for driving said cam drum 35, the same comprising a power shaft 43 journaled in bearings 44 mounted on the lower framework platform 11. Arranged to be controllably driven by said power shaft 43 through a suitable clutch mechanism 45 is a worm 46 which meshes with a worm gear 47 affixed to the cam drum shaft 36. Said power shaft 43 is driven by a pulley or the like 48 from any suitable source of power. The clutch mechanism 45 may be controlled by its shift lever 49 through a pivoted foot treadle lever 50, which is caused to move by the operator's foot.

table 13, as may be most convenient to the operator. The pelt or skin is so arranged that the thicker head end *a* thereof lies toward the left end of the presser member or table, and the left end portions of the rolls 33 (as viewed in Fig. 2) are tapered toward their extremities, as at 62, whereby to provide clearance space so that said rolls 33 may pass over said thicker head end *a* without disturbing or interfering with the operative contact and pressure of the main portions of the rolls upon the pelt or skin.

The pelt or skin being thus operatively spread upon the presser member or table 13, the operator thereupon depresses the foot treadle lever 50 so as to throw in the clutch 45, and thus cause transmission of driving power to the cam drum 35. As the cam drum 35 rotates, its cam member 42 exerts an upward thrust upon the elevator shaft 16, whereby the presser member or table 13 is caused to rise. As such rising movement of the presser member or table 13 is initiated, it first engages the weight pressed clamp bar 24, whereby the medial portion of the pelt or skin carried thereby is firmly clamped and held against lateral shift between the same and said clamp bar. Thereafter, as the presser member or table continues to rise, it engages the rotating stretching and smoothing rolls 33 so that the latter contact and press against the pelt or skin A respectively at opposite sides of the medial portion thereof. Continued rising movement of the presser member or table, due to the angularly divergent work supporting faces 14 thereof, causes the swingable frames by which the rolls 33 are carried to respectively swing outward, and thereby causes the rotating rolls 33 to travel outwardly over the pelt or skin pressed thereagainst by the upward thrust of the presser member or table. Such outward travel of the rolls 33, in conjunction with the outwardly sweeping rotative contact and pressure thereof upon the pelt or skin A, exerts a strong stretching and smoothing effect upon the latter in opposite lateral directions leading from its medial portion, so that the wrinkles or distortions thereof are quickly ironed out leaving the skin substantially smooth and flat (see dotted representations in Fig. 3). To increase the frictional engagement of the rolls 33 with the pelt or skin A, and thereby the efficiency of the stretching and smoothing action thereof, the surfaces of said rolls may be suitably roughened, as, e. g., by longitudinally ribbing or fluting the same, as shown. An additional advantage of so surfacing said rolls 33, is that the same also serve during the stretching and smoothing action to remove grease from the pelt or skin, when such treatment is desirable.

The stretching and smoothing action continues until the pelt or skin has been entirely traversed by the rolls 33, and said rolls pass off of the sides of the presser member or table 13, as the latter approaches the limit of its upward movement.

As the rolls 33 are pushed off the presser member or table 13, the swingable frames carrying the same are thereby caused to reach the limit of their outward swinging movement, which movement swings inwardly the tail members 31 of the frame lever arms 28 to their inward limit. Releasable detent means is provided for engaging the inswing tail members 31, whereby to retain the swingable frames and their rolls 33 in outswung positions, while the presser member or

table 13 completes its upward movement and thereupon, as controlled by the actuating cam member 42, reverses its movement and descends to normal lowered position. Said detent means 5 comprises spring urged latch members 63 which are fixed on rock shafts 64 journaled in and between the frame bracket arms 21. Affixed to the tail members 31 of the swingable roll carrying frames are projecting catch-pieces 65 which are engageable by the latch members 63. Carried by a bracket 66 extending from an end of the presser member or table 13 is an upstanding post 67 which accompanies the up and down movement of the presser member or table 13. Affixed to said post 67 is a laterally projecting trip-piece 68. When the presser member or table occupies its normal lowered position, said trip-piece 68 engages the tail ends of adjacent latch members 63, at one end of the machine, whereby to rotate the rock shafts 64 and thereby upswing all the latch members 63 to released positions (see Fig. 1). When the presser member or table 13 begins its upward operative movement, said trip-piece 68 is carried away from the latch-members 63, thereby permitting the same, as yieldably tensioned by their springs, to swing down to operative positions, as determined by stop projections 69, ready to engage the catch-pieces 65 of the swingable frame tail members 31, so as to hold the swingable frames and their rolls 33 outswung while the presser member or table 13 returns to normal lowered position (see full line representations in Fig. 3). As soon as the presser member or table 13 arrives at its normal lowered position, the trip-piece 68 again releases the latch members 63, so that the swingable frames and their rolls 33 may, under the influence of the pull springs 34, return to their normal inswing positions above the presser member or table. 40 Upon these occurrences, the clutch 45 is released, whereupon the stretched and smoothed pelt or skin A is removed, and replaced by another pelt or skin desired to be treated by a repetition of the described machine operations.

45 Optionally, additional means may be provided for guiding and holding the clamp bar 24 true to its path of ascent and descent cooperatively with the operation of the presser member or table 13. Illustratively, as shown, such additional guide means comprises a guide channel 70 formed in the post 67 at one end of the machine, in which is slidably engaged one end extension 71 of the clamp bar 24; and a stationary channeled guide rod 72 dependent from a support 73 which is affixed to a bracket arm 21 at the opposite end of the machine, in the guide channel of which guide rod 72 is slidably engaged the opposite end 74 of said clamp bar 24.

60 We are aware that various changes could be made in mechanism as above described and as shown in the accompanying drawings without departing from the scope of this invention as defined in the following claims. It is therefore intended that all matter contained in the above 65 description or shown in the accompanying drawings shall be interpreted as illustrative and not in a limiting sense.

We claim:

1. In mechanism for the purposes described, a vertically reciprocable table having laterally and oppositely downwardly inclined work supporting faces obtusely divergent from its medial longitudinal portion, said table being adapted to support the work deposited thereon for lateral extension from the medial portion thereof over said respec-

En el desarrollo de los sistemas esenciales, a través de la respiración celular, se libera el oxígeno que se difunde en el interior de las células y se combina con los hidroxilos de agua para formar agua hidroxilada. El resultado es la producción de agua hidroxilada, que es la base de la vida.

3.6) **Mediacion** en el arbitraje: un proceso de acuerdo entre las partes en conflicto y el tercero. Mediación es el proceso de negociación entre las partes en conflicto, en el que el tercero (mediador) actúa como intermediario entre las partes, buscando una solución que sea aceptable para ambas. El mediador no tiene autoridad para imponer una solución, sino que su función es facilitar la comunicación entre las partes y sugerir alternativas que puedan ser aceptadas por ambas.

11. El Mercantilismo propone a la economía de sus estados y el desarrollo industrial, industrialización y desarrollo urbano, arquitectura, cultura, educación, formación científica y tecnológica, y en las relaciones exteriores se apoya en la formación de una confederación europea.

erse the parts of the work supported thereon, a pair of dependent normally inswung but outwardly swingable pivoted frames by which said rolls are respectively carried, means to yieldably urge said frames and their rolls to normally inswung positions above the lowered table and to thrust said rolls against the table supported work while they traverse the latter during outward swinging movement of their carrying frames induced by ascending movement of the table, and means for rotating said rolls in directions whereby to apply stretching and smoothing effect to the supported work outwardly from the medial portion thereof.

10. In mechanism for the purposes described, a table having laterally and oppositely downwardly inclined work supporting faces obtusely divergent from its medial longitudinal portion, a vertically reciprocable elevator means to carry said table, a rotary cam means for actuating said elevator means, power transmission means for driving said cam means including a normally released clutch and means for manipulating said clutch, a work clamping means aligned with and opposed to the medial longitudinal portion of said table, means to yieldably urge said clamping means toward the table, means to space said clamping means from the table when the latter occupies its normal initial lowered position, stretching and smoothing rolls cooperative with each inclined face of said table adapted to traverse the parts of the work supported thereon, a pair of dependent normally inswung but outwardly swingable pivoted frames by which said rolls are respectively carried, means to yieldably urge said frames and their rolls to normally inswung positions above the lowered table and to thrust said rolls against the table supported work while they traverse the latter during outward swinging movement of their carrying frames induced by ascending movement of the table, and means for rotating said rolls in directions whereby to apply stretching and smoothing effect to the supported work outwardly from the medial portion thereof, said latter means comprising roll driving power transmission means including a telescopic drive shaft for each roll and universal joint connections between each roll and its telescopic shaft and between each telescopic shaft and said roll driving power transmission means.

11. In mechanism for the purposes described, a table having laterally and oppositely downwardly inclined work supporting faces obtusely divergent from its medial longitudinal portion, a vertically reciprocable elevator means to carry said table, a rotary cam means for actuating said elevator means, power transmission means for driving said cam means including a normally released clutch and means for manipulating said clutch, a work clamping means aligned with and opposed to the medial longitudinal portion of said table, means to yieldably urge said clamping means toward the table, means to space said clamping means from the table when the latter occupies its normal initial lowered position, stretching and smoothing rolls cooperative with each inclined face of said table adapted to traverse the parts of the work supported thereon, a pair of dependent normally inswung but outwardly swingable pivoted frames by which said rolls

are respectively carried, means to yieldably urge said frames and their rolls to normally inswung positions above the lowered table and to thrust said rolls against the table supported work while they traverse the latter during outward swinging movement of their carrying frames induced by ascending movement of the table, each carrying frame having an upwardly extending tail arm, detent means operative to engage said tail arms when inswung whereby to hold said frames outswung with the rolls disposed beyond the path of table movement, to which positions said rolls are moved by ascent of the table, detent trip means carried by the table and operative to release said detent means when the table occupies its lowered position, whereby to thereupon permit return of said frames and rolls to normal inswung positions, and means for rotating said rolls in directions whereby to apply stretching and smoothing effect to the supported work outwardly from the medial portion thereof.

12. In mechanism for the purposes described, a table having laterally and oppositely downwardly inclined work supporting faces obtusely divergent from its medial longitudinal portion, a vertically reciprocable elevator means to carry said table, a rotary cam means for actuating said elevator means, power transmission means for driving said cam means including a normally released clutch and means for manipulating said clutch, a work clamping means aligned with and opposed to the medial longitudinal portion of said table, means to yieldably urge said clamping means toward the table, means to space said clamping means from the table when the latter occupies its normal initial lowered position, stretching and smoothing rolls cooperative with each inclined face of said table adapted to traverse the parts of the work supported thereon, a pair of dependent normally inswung but outwardly swingable pivoted frames by which said rolls are respectively carried, means to yieldably urge said frames and their rolls to normally inswung positions above the lowered table and to thrust said rolls against the table supported work while they traverse the latter during outward swinging movement of their carrying frames induced by ascending movement of the table, each carrying frame having an upwardly extending tail arm, detent means operative to engage said tail arms when inswung whereby to hold said frames outswung with the rolls disposed beyond the path of table movement, to which positions said rolls are moved by ascent of the table, detent trip means carried by the table and operative to release said detent means when the table occupies its lowered position, whereby to thereupon permit return of said frames and rolls to normal inswung positions, and means for rotating said rolls in directions whereby to apply stretching and smoothing effect to the supported work outwardly from the medial portion thereof.
